(57) **CLAIM**

The ornamental design for a digital laser pointer, as shown and described.

DESCRIPTION

FIG. 1 is a front elevational view of my new design of a digital laser pointer;

FIG. 2 is a back elevational view thereof;

FIG. 3 is a left side elevational view thereof;

FIG. 4 is a right side elevational view thereof;

FIG. 5 is a top elevational view thereof;

FIG. 6 is a bottom elevational view thereof; and,

FIG. 7 is an isometric elevational view.
